UNITED STATES PATENT OFFICE.

WARREN FUHRMANN, OF NEWARK, NEW JERSEY.

LINK-MESH FABRIC.

1,231,345.

Specification of Letters Patent. Patented June 26, 1917.

Application filed March 1, 1916. Serial No. 31,323.

To all whom it may concern:

Be it known that I, WARREN FUHRMANN, a citizen of the United States, and a resident of Newark, in the county of Essex and State 5 of New Jersey, have invented certain new and useful Improvements in Link-Mesh Fabrics, of which the following is a specification.

The object of the present invention is to 10 provide an improved construction of a fabric that is formed of a set of rings that are inter-connected by a set of links, wherein the links can be partially formed, then each threaded on to a series of the rings, and then 15 the links are closed to secure them to the rings, by means of a simple form of die or bending member, that will close the rings to form eyes at several portions, by merely pressure in one direction on the outside of 20 the links.

A further object of the invention is to 25 provide a new form of link for such a fabric, in which the radial arms are first bent to form half circles with the extremities of 30 the arms projecting upward, and thereupon after the rings are placed on these arms, a simple die member is brought to engage the arms and will bend them inwardly so that each forms a substantially complete circle 35 to inclose one of the rings. By reason of the novel shape of the arms in the blank, a final bending operation to complete the eye or circle, will produce the desired circle or eye, by simply the application of the closing die, and without the employment of an interior anvil or shaping member.

In the accompanying drawing, showing 40 one embodiment of my invention, Figure 1 is a view on one face of the fabric, and Fig. 2 is a view of the opposite side, all the views showing the parts considerably enlarged. Fig. 3 shows the blank for the link in plan, and Fig. 4 is an edge view of the same. Fig. 5 shows the bending operation for the link, 45 and Fig. 6 is a similar view of another form of link. Fig. 7 shows the link of Fig. 5 with two rings placed thereon. Fig. 8 is a plan of the parts as shown in Fig. 7. Fig. 9 is a section on the line 9—9 of Fig. 8. Fig. 10 shows the forming dies for the first operation, Fig. 11 shows the dies for the final operation, in the act of closing the link, and Fig. 12 is a cross section on the line 12—12 indicated in Fig. 7.

50 As shown in the drawing the fabric is formed of a set of rings 12 that are preferably flat rings. These rings are inter-connected by a set of links 13, in the form of a cross or spider, in the present instance having four arms 14. These arms are of considerable length relative to their width, and are made converging to the outer ends as indicated in Fig. 3.

The links 13 are first bent by suitable dies so that the inner half of each arm 14 is given 55 a form of a half circle, the centers of which lie in the plane of the central portion 16 of the blank as indicated in Figs. 5 and 7. This can conveniently be done by providing a die 17 having its top provided with four 60 semi-circular depressions 18 as indicated in Fig. 10, and a flat central portion 19. An upper die or punch 20 has four semi-circular projections 21 and a flat central portion 22, as shown in Fig. 10. A sleeve 23 is provided to slide on the lower die 17, and the punch 20 is sufficiently smaller than the sleeve bore to accomodate the thickness of the arms 14 as shown in Fig. 10. It will be clearly understood that these three die members 65 will produce the partly formed links as shown in Figs. 5 and 7 with the four arms 14 extending upward. Then four of the links 12 are placed on the arms 14, as indicated in Figs. 7 and 8. To bend down the 70 upstanding arms 14, a die member 24 is provided having four semi-circular depressions 25. The punch or upper die 20 is removed and the lower die advanced in the sleeve 75 bore to engage the extremities of the arms 14. The die 24 is then brought down, after the rings 12 have been applied, and the curved faces will engage the extremities of the four arms 14. These arms or rings by the curved faces 80 engaging them at their outer portions, will 85 bend inwardly. If these arms were of uniform width or were of less width at their inner portions, they would have a tendency to bend at the lower part of the straight portion. But by forming the arms converging 90 to the extremities, the end portions being narrower will tend to bend first, and hence the extremity of the arm will follow the curve 25 from its outer portion inwardly, as indicated in broken lines in Fig. 5, from the 95 upper part downward. This is also indicated in Fig. 11 where the arms are partly curved downward and inward. Therefore, the result of this construction of the arms is 100 that the upper or outer half will be caused 105 to bend first, and hence the extremity of the arm will follow the curve 25 from its outer portion inwardly, as indicated in broken lines in Fig. 5, from the 110 upper part downward. This is also indicated in Fig. 11 where the arms are partly curved downward and inward. Therefore, the result of this construction of the arms is 110

to form a half circle, and when the die 24 is brought all of the way down each arm 14 will have the extremity brought down adjacent the central portion 16, to form a substantially complete half circle 10 as indicated in Fig. 9. These circles will each inclose the link 12 as shown.

A fabric can thus be produced from a set of these blanks 13, by use of the bending dies, in which each link is connected with four rings, and each ring, except at the margins, is connected by four links. Fig. 1 shows one side of such a fabric, which is the side shown exposed. Fig. 2 shows the opposite side or face, on which the links are bent. But with the fabrics formed as they generally are, much smaller than shown in the drawing, there are usually from six to ten links to the inch, and the two opposite faces of the fabric are very similar in appearance. It will be observed that the flat central portions of all of the links are substantially parallel with the flat links 12, for the reason that the centers of the circular arms lie in this plane.

From Fig. 12 it will be seen that each of the arms 14 where it is first bent or curved at its connection with the center portion, 16, is given a curve in its cross section, that is, is made somewhat cylindrical, with the concave sides of the arms facing the central portion. This is for the purpose of giving the central portion 16 a substantially circular appearance on one face of the fabric, as clearly shown in this and other views. This curving of the arm will also have a strengthening effect where the arms are joined to the center connecting portion.

It will be understood that by reason of the tapering form of the arms of the spider, the final bending die 24 will produce the curving without the employment of an interior anvil or bending member. If these arms were made straight, and the die 24 employed, the arm 4 when extended inwardly would bend as indicated in Fig. 6, over the center portion, and would not form a complete circle

with the inner half. This is because the arm would bend first at its lower portion.

The dies shown in Figs. 10 and 11, and the method of forming the links, are not claimed in this application, but form subject matter of another application.

Having thus described my invention, what I claim is:

1. A link mesh fabric having substantially similar faces, composed of a set of rings interconnected by a set of links, the links each being in the form of a sheet-metal spider having a substantially flat central portion from which radiate elongated arms having straight side edges converging in width from the central portion, each arm being bent to form a substantially complete circle beyond and perpendicular to the flat central portion, the centers of the circles of the arms lying in the plane of said central portion, the circular arms inclosing the rings.

2. A link for a link mesh fabric, composed of a sheet-metal spider having a substantially flat central portion from which radiate elongated arms, said arms having straight side edges converging in width from the central portion, each arm being bent to form a substantially complete circle beyond and perpendicular to the flat central portion, the centers of the circles of the arms lying in the plane of said central portion.

3. A link mesh fabric having substantially similar faces, composed of a set of rings interconnected by a set of links, the links each being in the form of a sheet-metal spider having a substantially flat central portion from which radiate elongated arms having straight side edges converging in width from the central portion, each arm being bent to form a substantially complete circle beyond and perpendicular to the flat central portion, and each arm being transversely curved at its portion adjacent the central portion of the link to form a substantially circular central portion.

WARREN FUHRMANN.
